DESIGN FOR A COMBINED SCORE TABLE AND BOWLING ALLEY SERVICE UNIT OR SIMILAR ARTICLE

Ellery J. Cloutier, Muskegon, Mich., assignor to
The Brunswick - Balke - Collender Company,
Chicago, Ill., a corporation of Delaware

Application April 7, 1941, Serial No. 100,185

Term of patent 14 years

To all whom it may concern:

Be it known that I, Ellery J. Cloutier, a citizen of the United States, residing in the city of Muskegon, county of Muskegon, State of Michigan, have invented a new, original, and ornamental Design for a Combined Score Table and Bowling Alley Service Unit or Similar Article, of which the following is a specification, reference being had to the accompanying drawing, forming a part thereof.

bined score table and bowling alley service unit or similar article, showing my new design;

The opposite side of the unit is substantially the same as that shown.

I claim—

The ornamental design for a combined score table and bowling alley service unit or similar article, as shown and described.

ELLERY J. CLOUTIER.
